PAPER INDICATED DOBBY

Clarence R. Kronoff, Worcester, Mass., assignor
to Crompton & Knowles Loom Works, Worcester, Mass., a corporation of Massachusetts

Application May 21, 1952, Serial No. 289,070

21 Claims. (Cl. 139—68)

1

This invention relates to improvements in paper indicated dobbies for looms and it is the general object of the invention to provide a dobbby wherein a set of elements are first moved to perform a pattern reading operation and are thereafter moved to position the dobbby hooks in accordance with the pattern reading.

In the usual paper indicated dobbby it is customary to employ lightweight pattern reading elements which are periodically presented to a pattern surface having perforations through which some of the elements pass and having blank or non-perforated parts which support other of the elements. The pattern readers are utilized in such instances to position hook lifting means constituting a separate set of parts which are then moved by an actuator to determine the position of the hooks with respect to their knives. The force required to lift a hook is ordinarily greater than that which a blank part of the paper pattern can withstand without being punctured by the reading elements and it is for this reason that two separate sets of parts are introduced between the paper pattern and the hooks.

It is an important object of the present invention to eliminate the aforesaid second set of parts and utilize the pattern reader elements not only to read the pattern but also to effect lifting of the hooks. This result is accomplished by mounting the pattern readers on a movable carrier or the like which first moves the reading elements toward the paper pattern to read it, after which the reader elements are locked to the carrier in the positions which they occupy as determined by the paper pattern, and are then lifted to elevate the hooks which should be raised.

In the usual paper indicated dobbby the pattern readers remain in reading position for a considerable period of the cycle of operation of the dobbby and while the readers are in reading position the paper pattern cannot be moved. It is a further object of the present invention to effect pattern reading during a comparatively short interval of the dobbby cycle, store the reading, and then move the pattern reading elements away from the pattern toward the hooks. In this way the pattern readers have only momentary reading relation with respect to the pattern and the pattern is free to be moved during the greater part of the cycle of the dobbby to present a new surface in reading position.

When the invention is applied to a so-called double index dobbby one pattern reading oper-

2

ation is performed for two picks of the loom and when the pattern reading has been completed indications for two successive picks of the loom are stored due to locking of the pattern readers with respect to the aforesaid carrier. It is a further object of the invention to give the carrier two hook controlling motions between successive reading operations, one of these motions being primarily for one set of hooks and the other motion being primarily for the other set of hooks. As will be set forth hereinafter the carrier is raised to a hook controlling position prior to the working stroke of one of the knives. It is then lowered to an intermediate non-controlling position to avoid exerting a force on hooks already engaged with the other knife, and is then returned to the hook controlling position prior to the working stroke of the other knife. The stored indications for these two picks of the cycle are retained during the two movements of the carrier due to the fact that the lock mechanism will be in locking position from a time shortly after completion of reading of the pattern until after the second set of hooks have been engaged by the other knife.

When the aforesaid carrier has a motion toward the paper pattern the pattern reading elements should be unlocked so that the force which they exert on the paper pattern will be due to their weight only. In order to accomplish this result it is another object of the invention to cause a slight pause or dwell in the motion of the carrier toward the pattern to arrest any downward momentum which the elements might have acquired due to descent of the carrier. The lock mechanism can also move to unlocking position during this slight pause or dwell.

It is a further object of the invention to provide a dobbby unit comprising a set of pattern reading and hook lifting elements movable on a carrier and a still further object is to provide the unit with lock mechanism for the elements to form an assembly usable on a dobbby.

In order that the invention may be clearly understood reference is made to the accompanying drawings which illustrate by way of example the embodiments of the invention and in which:

Fig. 1 is a rear elevation of a dobbby made according to the present invention,

Fig. 2 is a horizontal enlarged section on line 2—2, Fig. 1,

Fig. 3 is a vertical section on line 3—3, Fig. 2, showing the locking mechanism,

Fig. 4 is a vertical section on line 4—4, Fig.

2, showing the mechanism by which the carrier for the pattern readers is moved.

Fig. 5 is an enlarged vertical transverse section on line 5—5, Fig. 2.

Fig. 6 is a detail enlarged vertical section on line 6—6, Fig. 2.

Fig. 7 is an enlarged vertical section on line 7—7, Fig. 2, showing the mechanism for disabling the locking means shown for instance in Fig. 3 to enable the dobby to be leveled.

Fig. 8 is a diagrammatic view similar to a part of Fig. 3 showing the pattern reading elements performing a reading operation.

Fig. 9 is a view similar to Fig. 8, but showing the lock mechanism in position to store the indications derived from the paper pattern.

Fig. 10 is a view similar to Fig. 9 but with the dobby hooks added and indicating a hook locating operation derived from motion of the aforesaid carrier toward the hooks, and

Fig. 11 is an enlarged detail horizontal section on line 11—11, Fig. 10, showing the relation between one of the lock bars and one of the pattern reading elements.

Referring more particularly to Figs. 1 and 2, the loom frame indicated at 1 supports a double index dobby designated generally at D and including front and back side or frame plates 2 and 3, respectively. These plates guide top and bottom harness lifting knives 4 and 5, respectively, which are actuated through connectors 6 by a three armed lever 7 oscillated by a loom driven upright rod 8 having a complete reciprocation in a two-pick cycle of the loom. Harness lifting jacks 9 are pivotally mounted on a pin 10 extending between and secured to the plates 2 and 3, and each jack as a dobby back lever 11 having pivoted to the ends thereof upper and lower dobby hooks 12 and 13, respectively. These hooks are for cooperation with the knives 4 and 5, respectively, and when the upper and lower hooks of any lever 11 are disengaged from their knives the jack will be to the left, Fig. 1, so that the corresponding warp lifting harness (not shown) will be down. If one or another of the hooks of a lever 11 is engaged with its knife the lever will then move to the right to effect lifting of the corresponding harness frame through the associated jack 9.

A shaft 15 is journaled for rotation with respect to the dobby in right and left bearings 16 and 17, respectively, Fig. 2, and is driven by a loom operated chain 18 which effects rotation of shaft 15 once in two picks of the loom. Shafts 15 has secured thereto a worm 19 which meshes with a worm wheel 20 secured to a shaft 21 journaled for rotation on the dobby and having secured thereto a paper pattern cylinder 22. The worm 19 effects step by step advance movements of the cylinder 22 every second pick of the loom. Trained over the cylinder is a paper pattern P below the hooks 12 and 13 having indications arranged in transverse rows, these indications being either perforations 25 or blank or unperforated parts 26. These rows of perforated and non-perforated parts are arranged in parallel pairs, one row of the pair for the set of upper hooks 12 and the other row for the set of lower hooks 13. When the paper pattern is temporarily at rest one pair of these rows will be in reading position. It is customary in dobby construction to employ a yieldable clutch between worm wheel 20 and shaft 21 to permit manual turning of cylinder 22 when shaft 15 is at rest, but this

clutch is omitted from the drawings for the sake of clarity.

Except as noted hereinafter the matter thus far described is of usual construction, the knives 4 and 5 being reciprocated in opposite directions by the rocker lever 7 and the paper pattern being moved progressively by a step and step motion to present new pairs of rows of perforated and non-perforated indicating parts thereof to reading position. It will be understood that the bottom knife 5 is shown in Fig. 1 as being in the position which it occupies at the beginning of a working stroke thereof to the right, and that knife 4 is shown as having completed a working stroke and is in position to start an idle return stroke. On the next beat of the loom knife 5 will have a return stroke and knife 4 will have a working stroke. In the present instance the hooks 12 and 13 are normally down in the paths of their respective knives but can be lifted to be out of the paths of their knives.

In carrying the invention into effect a horizontally extending unit U including a carrier C of elongated form is mounted for vertical reciprocation between the cylinder 22 and bottom hooks 13. This carrier is guided in its vertical motion by upright guides 30 secured to supports 31 fastened to the dobby plates 2 and 3. The carrier is held against endwise motion by stops 32, see Fig. 5, secured thereto at 33 and engaging the associated guides 30. One of the bearings 34 for the pattern cylinder shaft 21 is indicated in Fig. 5 and a collar 35 secured to the shaft 21 aligns the cylinder horizontally with the carrier C.

As indicated more particularly in Fig. 3 the carrier has mounted for vertical sliding motion therein two parallel rows of pattern reader and hook lifter elements 36 and 37. Each of these elements comprises a slender downwardly extended stem or wire 38 and an upper cylindrical head 39 and a collet 40 below the head 39. The parts 38, 39 and 40 are preferably integral and can move vertically on the carrier, the stems being slidable in holes 41 in the lower part of the carrier and the heads and collars being slidable in larger holes 42 opening upwardly in the upper part of the carrier. The head and collet of each element are connected by a continuation of the stem. The stems extend below the carrier and the heads preferably above it.

The carrier is provided with lock mechanism by which the reading and lifting elements 36 or 37 can be locked either in high or low position against downward movement with respect to the carrier. As shown more particularly in Fig. 3 this lock mechanism comprises a pair of lock bars 45 and 46 located respectively at the right and left sides of the carrier C as viewed in Fig. 3. These lock bars are mounted at their ends on levers 47 and 48, respectively, which are pivoted at 49 at their lower ends to downward extensions 50 at the ends of the carrier. There are two each of the levers 47 and 48, and the upper ends of each pair of levers 47 and 48 are connected by a tension spring 51 which tends to draw the bars 45 and 46 toward each other to the position shown in Fig. 3.

The lock bars 45 and 46 are movable in a substantially horizontal direction in slots 52 and 53 extending horizontally and lengthwise on opposite sides of the carrier C. These slots communicate with the upper larger bores 42 in the carrier. The edges of the lock bars may be formed as shown in Fig. 11 with notches 55 to fit around the slender stems 38 so that the parts 56 of the

bar adjacent to each notch can extend under a relatively large part of either a head 39 or a collet 40 of the associated elements 36 or 37.

Each lever 48 has a finger 60 which projects under a similar finger 61 on the adjacent lever 47 and whenever a lever 48 is moved to the left from the position shown in Fig. 3 its finger 60 will raise finger 61 of the adjacent lever 47 and cause simultaneous rocking of the latter to the right. The two bars 45 and 46 and their associated levers and the spring 51 may be considered as lock mechanism movably mounted on the carrier C so that it can occupy either locking or non-locking position with respect to the pattern reader and lifter elements 36 and 37. The unit U and the lock mechanism may be considered as an assembly designated generally at A.

As shown herein the lock bar 46 is pivotally connected as at 65 to two laterally extending rods 66 each having a pivotal connection 67 with a depending arm 68 secured in angularly adjusted position on a rock shaft 69 by a set screw 70. The lower end of one of the arms 68 cooperates with a cam 71 secured to a rotating shaft 72 one end of which has secured thereto a mitre gear 73 meshing with a second mitre gear 74 secured to previously described shaft 15. The gears 73 and 74 are of the same size so that shaft 72 completes a rotation in two picks or beats of the loom. Shaft 72 is journaled for rotation in bearings 75 secured to the dobby frame. Cam 71 has a relatively long low dwell 76, a shorter high dwell 77, and inclines 78 joining the dwells. If desired each connection 67 may include a pin 79 on arm 68 fitting into a slot 80 formed in the adjacent end of rod 66. During operation of the dobby the cam 71 will effect momentary rocking of the arms 68 to the left as viewed in Fig. 3 to cause the lock bars 45 and 46 to move from the locking position shown in Fig. 3 to a non-locking position, after which continued rotation of cam 71 will enable the lock bars under action of springs 51 to return to locking position and remain in that position so long as the low dwell 76 controls the position of the lock mechanism.

The carrier C has already been described as being mounted for vertical rising and falling motion and this motion is caused by operating means shown in detail in Fig. 4. Shaft 72 has a cam 85 secured thereto for cooperation with an actuator lever 86 secured at 87 to one end of a transverse shaft 88 rockable in bearings 89 fixed with respect to the dobby. The other end of shaft 88 has an arm 90 secured thereto at 91 and as the cam rotates a roll 92 on lever 86 located in a cam groove 93 will cause the right end of lever 86, Fig. 4, and the end of arm 90 to rise and fall in a time relation which will be described. The carrier C has the ends thereof provided with gudgeons 94 which pass through slots 95 in the lever 86 and arm 90. The carrier is therefore raised and lowered by action of the cam 85 when the dobby is in operation. The cam has a low dwell 96, a higher dwell 97, and actuating areas or points 98 and 99 connecting the dwells and located on opposite sides of the dwells. The areas or points 98 and 99 extend farther from the axis of the cam than the dwell 97.

In operation, it may be assumed that roll 92 is in the low dwell 96 so that lever 86 has been turned to its extreme clockwise position as viewed in Fig. 4 to lower the carrier C to its lowest position. The elements 36 and 37 will therefore be able to read the pattern of the two rows of indication parts of the paper pattern under them

and some of these elements will pass through perforations and will be in low position with respect to the carrier while others will engage unperforated parts of the pattern and will be in high position with respect to the carrier. At this time the high dwell 77 of cam 71 will hold the lock bars 45 and 46 in non-locking position so that the parts will be in the position indicated diagrammatically in Fig. 8. In that figure it is assumed that a right hand element 36 has passed through a perforation while a left hand element 37 has engaged an unperforated part of the pattern.

Immediately after the elements have completed the pattern reading operation the cam 71 will present one of its inclines 78 to the associated arm 68 and the latter will rock in a counter-clockwise direction, Fig. 3, to enable the springs 51 to move the lock bars 45 and 46 to the locking position shown diagrammatically in Fig. 9 while the carrier is still in low position. As soon as the lock bars have moved to locking position the indications given by the pattern reader and hook lifter elements will be stored with respect to the carrier. As shown in Fig. 9 the right hand element will have its head 39 resting on the lock bar 45 whereas the left hand element 37 will have its collect 40 resting on the lock bar 46. This locking and indication storing relation will continue so long as the low dwell 76 of cam 71 controls the lock mechanism.

As cam 85 turns in the direction of arrow a, Fig. 4, it will rock lever 86 in a counter-clockwise direction, Fig. 4, and in doing so will raise the carrier and elements 36 and 37 away from the pattern and complete their upward motion to hook controlling position shortly before bottom knife 5 begins an outward working stroke. During upward motion of the carrier the elements 36 and 37 in high position will be supported by lock bars, and as shown herein the elements in low position will also be supported by the lock bars, although the low elements need not be thus supported. During this first upward motion of the carrier any element 36 or 37 which is locked in low position will permit the hook registered with it to remain in the path of its knife, and conversely any element which is locked in high position with respect to the carrier will raise its hook out of the path of its knife. This is illustrated in Fig. 10, wherein an upper hook 12 is shown as associated with a hook lifter wire 105 in register with an element 36 in low position, while a lower hook 13 is positioned by a hook lifter wire 106 registering with an element 37 in high position. These wires 105 and 106 may be similar to wires customarily used in dobbies and their upper ends may be hooked over support guides 107 and their lower ends may pass through a guide 108, see Fig. 1.

As soon as area or point 98 of cam 85 has raised the carrier to its extreme high position the knife 5 will start a right hand working stroke as viewed in Fig. 1 and any hook which has been permitted to remain in the path of the knife due to the fact that the associated element 37 is in low position will be engaged by the knife and be moved thereby to the right, but any hook 13 which has been raised out of the path of the knife 5 due to the fact that its associated element 37 is in high position with respect to the carrier will remain idle. In Fig. 10 the hook 13 shown in full lines is assumed to have been controlled by an element 37 in high position relative to the carrier, whereas the hook shown in dotted lines has

been permitted to remain in its normal low position.

At this time in the operation of the dobby it is likely that one or more of the top hooks 12 will be engaged with the knife 4 which has just completed its working stroke and is about to return on an idle stroke. When the carrier rises to its high position it lifts the wires 105 as well as wires 106. Such hooks 12 as were not engaged with knife 4 will be free to move upwardly under action of the corresponding wires 105 and elements 36 without effecting operation of the dobby, but any hook 12 engaged with the knife 4 at this time will resist upward movement if its lifter wire 105 were raised into engagement with it. In order to prevent this engagement the hooks 12 are arched upwardly as at 109, and a wire 105 can therefore be raised to the high position shown in Fig. 1 without engaging its corresponding hook 12 if the latter is held by the knife 4.

As the top knife starts its return motion to the left as viewed in Fig. 1 the cam 85 will turn sufficiently to effect clockwise turning of lever 86, see Fig. 4, to lower the carrier to an intermediate position and therefore permit downward motion of any lifter wire 105 corresponding to a hook engaged with knife 4. Descent of the carrier continues until roll 92 enters high dwell 97 at which time the wires 105 are low enough to permit their hooks to move to the left, Fig. 1, as the knife 4 completes its return motion. The carrier will be held in its intermediate position until knife 4 releases any hooks previously engaging it.

Preparatory to the working stroke of knife 4 which occurs on the next beat or pick of the loom the cam 85 will have turned sufficiently to return the carrier C to its high hook controlling position due to location of roll 92 in the high area or point 99 in the cam groove 93. As soon as top knife 4 has engaged the hooks 12 which have been permitted to remain in its path there is no longer need for the carrier to remain up, and cam 85 therefore by continued motion effects another clockwise turning of lever 86, Fig. 4, to lower the carrier.

In the down motion of the carrier however it is necessary to effect unlocking of elements 36 and 37 from the carrier before they engage the paper pattern. As shown herein unlocking occurs while carrier C is temporarily at rest. Cam groove 93 has a slight dwell 110 which produces a momentary pause or dwell in the down motion of the carrier. During this dwell the cam 71 by operation of the other of its inclines 78 rocks lever 68 to the left, Fig. 3, and thus moves the lock mechanism to unlocking position as shown in Fig. 8. The short dwell 110 momentarily stops down motion of the elements 36 and 37 to arrest their momentum. Thereafter continued turning of cam 85 will move the roll 92 back into the low dwell 96 and the carrier will again move to low pattern to permit the unlocked elements 36 and 37 to perform another pattern reading operation. Because of the fact that the momentum of the elements has been arrested, the only force they exert on the paper during the reading operation is that due to their weight. While the unlocking has been described as occurring during the pause caused by dwell 110, the invention is not necessarily limited to unlocking at this time.

Before the second reading of the pattern it will have been necessary for the pattern to move one

step to present another pair of rows of perforated and unperforated indicating parts thereof to reading position, and this motion of the pattern will have been effected at any time during the period in the operation of the dobby between the time the carrier moves the elements 36 and 37 away from the paper pattern and the time when the carrier is again in low enough position to effect the next reading of the pattern. It will be understood from the preceding description that this period in the cycle is relatively long so that the worm 19 will have ample time to give the cylinder 22 a gradual turning motion. This period of time can be longer than that existing in the usual paper indicated dobby due to the fact that as soon as the pattern has been read the elements 36 and 37 are moved away from the paper and the latter is therefore free to turn. In the usual paper indicated dobby the readers remain in reading position until after the top knife has picked up the hooks which have been indicated for engagement by it.

It may be desirable to level the dobby to enable the harnesses to come to a common position, in which event some provision must be made for relinquishing the control of the hooks which would otherwise be exercised by the elements 36 and 37. To effect leveling the shaft 69 has a collar 115 secured thereto by a set screw 116 and the collar has projecting therefrom a stop pin 117. A lock pawl 118 is pivoted on a pin 119 secured to the dobby, see Figs. 2 and 7. Ordinarily the rocking of shaft 69 under action of cam 71 will move the collar and the pin 47 from the full line position shown in Fig. 7 to the dotted line position, permitting the lock pawl 118 to remain down on a stationary stop pin 120. The locking mechanism is therefore able to operate as already described hereinbefore. When however it is desired to level the dobby a hand wheel 121 secured to shaft 69 is turned in a clockwise direction as viewed in Fig. 7 until the pin 117 has moved to a position to the right of the pawl 118. During this operation the pawl will first be raised by the pin and then will fall behind the pin as shown in dot and dash lines at b, Fig. 7. Shaft 69 is thereby locked with the arms 68 moved to the left as viewed in Fig. 3 to hold the locking bars 45 and 46 in unlocking position. The dobby can therefore operate but the springs 51 will be unable to move the lock bars to locking position and although down motion of the carrier C will result in a reading of the pattern, as soon as the carrier is moved upwardly the elements 36 and 37, not being locked, are free to slide down on the carrier to their low positions and all of the hooks will therefore remain down to effect leveling.

From the foregoing it will be seen that the invention sets forth a simple paper pattern indicated dobby wherein a set of elements, such as 36 and 37, first move toward the pattern to read it and then move away from the pattern to a hook controlling position to determine the position of the hooks with respect to the lifter knives. Lock mechanism, such as lock bars 45 and 46, stores the reading of the pattern to enable the reading to be used after the elements have been removed from the pattern. During the reading operation the forces exerted on the paper are small and due to the weight only of the elements, but after locking the elements are able to exert a much larger force sufficient to lift the hooks. Certain features of the invention are not limited to double index dobbies, but when the invention

is applied to dobbies of that type indications for two successive picks are stored in the mechanism by a single reading of the pattern. The carrier is controlled in such manner as to lower the elements to an intermediate position during the return stroke of the knife which utilizes the indication for the second pick, thereby avoiding exertion of a lifting force on any hooks which may be engaged with that knife. The elements are then returned to high position to lift these hooks if they are to be disengaged from the knife on its next working stroke. The slight dwell in the down motion of the carrier after the second knife has started a working stroke arrests the momentum of the elements and also affords time for unlocking them before they are again presented to the pattern. The invention also sets forth a novel unit comprising the carrier and elements 36 and 37, and further shows an assembly wherein the lock mechanism is combined with the unit. The arrangement of the pattern, elements 36 and 37, and the hooks is such that a perforation in the pattern corresponds to an indication for the associated hook to be in the path of its knife. Furthermore, the dobby can be leveled by manually moving the lock bars to non-locking position relative to the elements.

Having now particularly described and ascertained the nature of the invention and in what manner the same is to be performed, what is claimed is:

1. In a loom dobby having a set of harness lifter hooks normally in the path of a reciprocating lifter knife, a paper pattern below the hooks having perforated and unperforated indicating parts, combined pattern reading and hook lifting elements which first have a movement toward the pattern to perform a pattern reading operation and then have a second movement away from the pattern toward the hooks, the elements registering with unperforated parts of the pattern being above the elements registering with perforated parts of the pattern upon completion of the pattern reading operation, and mechanism to lock the elements with respect to each other on completion of the first movement thereof, the elements which are above the other elements being effective to move the hooks in register therewith out of the path of the knife when said elements have said second movement thereof.

2. In a loom dobby having a set of harness lifter hooks normally in the path of a reciprocating lifter knife, a paper pattern below the hooks having perforated and unperforated indicating parts, an indicating part of the pattern being provided for each hook, a unit intermediate the set of hooks and the paper pattern having a pattern reading movement toward the pattern followed by a hook lifting movement away from the pattern toward the hooks and comprising a carrier and combined pattern reading and hook lifting elements movable vertically on the carrier, one element being provided for each hook and each indicating part of the pattern, the carrier when having said pattern reading movement causing the elements to perform a pattern reading operation upon completion of which certain elements will be in high position and other elements will be in low position relative to the carrier, and mechanism operative upon completion of the reading operation to lock the elements against downward motion relative to the carrier in their relative positions with respect to the carrier, the carrier when having said hook lifting

movement causing the elements locked in high position on the carrier to effect movement of the corresponding hooks out of the path of the knife.

3. The loom dobby set forth in claim 2 wherein in additional manually operated means is provided to prevent the mechanism from locking the elements relative to the carrier to enable all of said elements to be in low position relative to the carrier as the latter has said hook lifting movement to prevent lifting of any of the hooks when it is desired to level the dobby.

4. In a loom dobby having a set of harness lifter hooks normally in the path of a reciprocating lifter knife, a paper pattern below the hooks having perforated and unperforated indicating parts, an indicating part of the pattern being provided for each hook, a unit intermediate the set of hooks and the paper pattern moving first toward the pattern and then toward the hooks, said unit comprising a carrier and combined pattern reading and hook lifting elements slideable vertically on the carrier, the carrier when moving toward the pattern causing the elements to perform a pattern reading operation upon completion of which the elements registering with the perforated indicating parts of the pattern will be in low position relative to the carrier and the elements engaging unperforated indicating parts of the pattern will be in high position relative to the carrier, and mechanism operative upon completion of the pattern reading operation to lock the elements against downward motion relative to the carrier in their high and low positions on the carrier and co-operating with the carrier when the unit moves toward the hooks to cause the elements in high position on the carrier to effect movement of the hooks corresponding thereto out of the path of the knife, the hooks corresponding to the elements in low position remaining in the path of the knife.

5. In a loom dobby having a set of harness lifter hooks normally in the path of a reciprocating lifter knife, a paper pattern below the hooks having perforated and unperforated indicating parts, a set of combined pattern reading and hook lifting elements each registering with a hook and an indicating part of the pattern, means moving the elements toward the pattern to perform a pattern reading operation upon completion of which the elements registering with the perforated indicating parts of the pattern will be in low position relative to the means and the elements registering with the unperforated indicating parts of the pattern will be in high position relative to the means, mechanism operative upon completion of the pattern reading operation to lock the elements in their high and low positions on the means against downward motion relative to said means, and said means thereafter moving the elements while they are locked relative to the means toward the hooks to cause the elements in high position to effect movement of the hooks registered therewith out of the path of the knife.

6. In a loom dobby having a set of harness lifter hooks normally in the path of a reciprocating harness lifter knife having working and return strokes, a paper pattern below the hooks having perforated and unperforated indicating parts, an indicating part of the pattern being provided for each hook, a unit intermediate the hooks and paper pattern comprising a vertically movable carrier having combined pattern reading and hook lifting elements mounted thereon for vertical movement relative thereto, operat-

11

ing means for the carrier effective to lower the latter to cause the elements to perform a pattern reading operation upon completion of which certain of the elements will be in high position and other of the elements will be in low position relative to the carrier, mechanism thereupon locking the elements against downward motion relative to the carrier, said operating means thereafter raising said carrier to hook controlling position to cause the elements in high position relative to the carrier to effect movement of the hooks corresponding thereto out of the path of said knife prior to the beginning of the working stroke thereof and thereafter causing downward motion of said carrier subsequent to said beginning of the working stroke for a second pattern reading operation, and said mechanism acting to unlock said elements relative to the carrier subsequent to said beginning of said working stroke and prior to said second pattern reading operation.

7. A loom dobby as set forth in claim 6 wherein the operating means causes a slight dwell in said downward motion of the carrier to arrest momentum of said elements prior to said second pattern reading operation.

8. A loom dobby set forth in claim 7 wherein said mechanism unlocks said elements during said dwell in the downward motion of the carrier.

9. In a double index dobby operating on a two-pick cycle having two knives one of which has a working stroke on the first pick of the cycle followed by a return stroke on the second pick of the cycle and the second knife of which has a return stroke on the first pick of the cycle and a working stroke on the second pick of the cycle, a set of harness lifter hooks normally in the path of the first knife and a second set of harness lifter hooks normally in the path of the second knife, a paper pattern below said hooks having two rows of perforated and non-perforated indicating parts, one row for the first set of hooks and the other row for the other set of hooks, a unit intermediate said hooks and pattern comprising a carrier and two rows of combined pattern reading and hook lifting elements movable vertically on the carrier, and operating means for the unit effective during a two pick cycle to cause the unit to have a movement to a low pattern reading position, then have a first movement to a high hook controlling position, thereafter have a movement to an intermediate position in which the elements are out of control of the hooks, and then have a second movement back to high hook controlling position, the elements when the carrier is in said low position performing a pattern reading operation upon completion of which certain of the elements will be in high position and other elements will be in low position relative to the carrier, mechanism operative upon completion of the pattern reading operation prior to the beginning of said first movement of the carrier to high position to lock the elements against downward motion relative to the carrier, said operating means effective to complete said first movement of the carrier and elements to high hook controlling position prior to the working stroke of the first knife to cause the elements in the row corresponding to the first set of hooks and in high position relative to the carrier to effect movement of the corresponding hooks in said first set of hooks out of the path of the first knife, and the operating means being effective to complete the second movement of the carrier to high position prior to the working stroke of the second knife to cause the elements of the other row in high position relative to the carrier to effect movement of the corresponding hooks of the second set of hooks out of the path of said second knife.

10. A double index loom dobby set forth in claim 9 wherein said carrier operating means lowers the carrier and elements to an intermediate position in which the elements are out of control of the hooks subsequent to the beginning of the working stroke of the first knife and re-

12

turns the carrier and elements to hook controlling position prior to the beginning of the working stroke of the second knife.

11. The double index loom dobby set forth in claim 10 wherein the operating means effects descent of the unit toward the pattern subsequent to said return of the carrier and elements to hook controlling position and the mechanism holds the elements locked relative to the carrier until after said return of the carrier and elements to hook controlling position and unlocks the elements during said descent of the carrier toward the pattern.

12. In a double index loom dobby operating on a two-pick cycle having two knives one of which has a working stroke on the first pick of the cycle followed by a return stroke on the second pick of the cycle and the second knife of which has a return stroke on the first pick of the cycle and a working stroke on the second pick of the cycle, a set of harness lifter hooks normally in the path of the first knife and a second set of hooks normally in the path of the second knife, a paper pattern below said hooks having two rows of perforated and non-perforated indicating parts, one row for each set of hooks, a unit intermediate the hooks and pattern comprising a carrier and combined pattern reading and hook lifting elements movable vertically on the carrier, and operating means for the unit effective during a two pick cycle to cause the unit to have a movement to a low pattern reading position, then have a first movement to a high hook controlling position, thereafter have a movement to an intermediate position in which the elements are out of control of the hooks, and then have a second movement back to high hook controlling position, the elements when the carrier is in said low position performing a pattern reading operation upon completion of which certain of the elements will be in high position and other elements will be in low position relative to the carrier, mechanism operative upon completion of the pattern reading operation prior to the beginning of said first movement of the carrier to high position to lock the elements against downward motion relative to the carrier, said operating means effective to complete said first movement of the carrier and elements to high hook controlling position prior to the working stroke of the first knife to cause the elements in the row corresponding to the first set of hooks and in high position relative to the carrier to effect movement of the corresponding hooks in said first set of hooks out of the path of the first knife, and the operating means being effective to complete the second movement of the carrier to high position prior to the working stroke of the second knife to cause the elements of the other row in high position relative to the carrier to effect movement of the corresponding hooks of the second set of hooks out of the path of said second knife.

13. In a double index loom dobby operating on a two-pick cycle having two knives one of which has a working stroke on the first pick of the cycle followed by a return stroke on the second pick of the cycle and the second knife of which has a return stroke on the first pick of the cycle and a working stroke on the second pick of the cycle, a set of harness lifter hooks normally in the path of the first knife and a second set of harness lifter hooks normally in the path of the second knife, a paper pattern below said hooks having two rows of perforated and non-perforated indicating parts,

a unit intermediate the hooks and the pattern comprising a carrier and combined pattern reading and hook lifting elements slidable vertically on the carrier, operating means moving the carrier and elements to a low position to cause the elements to perform a pattern reading operation for the two successive picks of the cycle, certain of the elements being in high position and others being in low position relative to the carrier upon completion of the pattern reading operation, mechanism thereupon effective to store the reading for said two picks by locking the elements against downward motion relative to the carrier, said operating means thereafter moving the unit away from the pattern to a high hook controlling position to cause the elements in high position relative to the carrier to effect upward movement of the hooks corresponding thereto out of the paths of their respective knives prior to the beginning of the working stroke of the first knife and the operating means thereupon effecting movement of the unit to an intermediate position in which the elements are out of controlling position relative to the hooks while the second knife has said return stroke thereof and the operating means then returning the unit to high hook controlling position prior to the working stroke of the second knife.

14. In a double index loom dobby operating on a two-pick cycle having two knives one of which has a working stroke on the first pick of the cycle followed by a return stroke on the second pick of the cycle and the second knife of which has a return stroke on the first pick of the cycle and a working stroke on the second pick of the cycle, a set of harness lifter hooks normally in the path of the first knife and a second set of harness lifter hooks normally in the path of the second knife, a paper pattern below said hooks having two rows of perforated and non-perforated indicating parts, one row for the first set of hooks and the second row for the second set of hooks, a unit intermediate the hooks and pattern comprising a vertically movable carrier and combined pattern reading and hook lifting elements movable vertically relatively to the carrier, a cam which rotates once during each two-pick cycle having a low dwell and a high dwell and two actuating areas, one area on one side of said dwells and the second area on the opposite side of said dwells, mechanism to lock the elements against downward motion relative to the carrier, and operative connections between the cam and the unit causing the carrier to place the elements to perform a pattern reading operation when the low dwell of the cam controls the operative connections, said mechanism locking the elements relative to the carrier upon completion of the pattern reading operation so that some of said elements are in high position and others are in low position relative to the carrier, said operating connections and cam thereafter effective to lift the carrier and elements to a high hook controlling position when one of said actuating areas of the cam controls the operative connections to cause the elements in high position on the carrier to effect lifting of the hook corresponding thereto out of the paths of their respective knives prior to the beginning of the working stroke of the first knife, said operating connections and high dwell of the cam causing the carrier to be located out of control position relative to said hooks during part at least of the return stroke of the second knife, and said second area there-

after cooperating with said operating connections to return the carrier and elements to high hook controlling position to cause the elements in high position on the carrier again to effect lifting of the hooks corresponding thereto out of the paths of their knives prior to the beginning of the working stroke of the second knife.

15. A double index loom dobby set forth in claim 14 wherein said locking mechanism is effective to maintain the elements locked with respect to the carrier from the time in the operation of the dobby when the low dwell controls the position of the carrier until after the second actuating area of the cam has returned the carrier to high hook controlling position.

16. An assembly for loom dobby provided with a paper pattern and harness lifter hooks comprising an elongated carrier and combined pattern reading and hook lifting elements slidably mounted on the carrier and capable of assuming either high or low positions relative to the carrier when the latter is in the position it assumes when in use, and lock mechanism on the carrier to lock the elements against downward motion relative to the carrier when said elements are in either high or low position on the carrier.

17. An assembly as set forth in claim 16 wherein said elements are arranged in a row on the carrier and the lock mechanism comprises a lock bar extending lengthwise of the carrier and movable on the latter to one position to engage the elements and movable to another position out of engagement with the elements.

18. An assembly as set forth in claim 16 wherein the lock mechanism comprises two lock bars extending lengthwise of and mounted on the carrier for movement relative thereto, one lock bar on each side of the carrier, and wherein the elements are arranged in two parallel rows on the carrier between said bars, one row for each lock bar, and wherein resilient means normally draws said lock bars toward each other into engagement with the elements of their respective rows but yields to permit movement of said bars away from said elements to unlock the latter with respect to the carrier.

19. An assembly set forth in claim 16 wherein each element is elongated and has a head at the upper end thereof and a collet thereon below the head and the lock mechanism includes a lock bar to engage the under side of the head of an element in low position on the carrier and engage the under side of the collet of an element in high position on the carrier.

20. An assembly as set forth in claim 16 wherein the elements are arranged in two parallel rows on the carrier and the lock mechanism includes two parallel lock bars, one lock bar for each row of elements, mounted on the carrier for pivotal movement relative to the carrier into and out of engaging position with respect to elements of their respective rows.

21. An assembly as set forth in claim 20 wherein said lock bars are mounted on levers pivoted on the carrier and the levers have interengaging parts effective upon movement of one of said bars away from the row of elements corresponding thereto to cause movement of the other bar away from the row of elements corresponding to the other bar.
